UNITED STATES PATENT OFFICE

109,572

DESIGN FOR A PRESSURE OPERATED ELECTRIC SWITCH OR SIMILAR ARTICLE

Peirce van Vleck, Washington, D. C.

Application December 23, 1936, Serial No. 66,714

Term of patent 7 years

To all whom it may concern:

Be it known that I, Peirce van Vleck, a citizen of the United States, residing at 5425 Connecticut Avenue N. W., Washington, D. C., have invented a new, original, and ornamental Design for a Pressure Operated Electric Switch or Similar Article, of which the following is a specification, reference being had to the accompanying drawing, forming part thereof.

In the drawing,

Figure 1 is a perspective view of a pressure operated electric switch; and,

Figure 2 is a vertical elevation.

I claim:

The ornamental design for a pressure operated electric switch, or similar article, substantially as shown.

PEIRCE VAN VLECK.
